Primary Examiner — Elizabeth J Oswecki(74) *Attorney, Agent, or Firm* — W. Kevin Ransom; Moore & Van Allen, PLLC(57) **CLAIM**

The ornamental design for a user terminal enclosure, as shown and described.

DESCRIPTION

FIG. 1 is a front, right side perspective view of a user terminal enclosure showing our new design;

FIG. 2 is a front side view of the user terminal enclosure of FIG. 1;

FIG. 3 is a top side view of the user terminal enclosure of FIG. 1;

FIG. 4 is a back side view of the user terminal enclosure of FIG. 1;

FIG. 5 is a right side view of the user terminal enclosure of FIG. 1;

FIG. 6 is a left side view of the user terminal enclosure of FIG. 1; and,

FIG. 7 is a bottom side view of the user terminal enclosure of FIG. 1.

The broken lines shown in the drawings represent portions of the user terminal enclosure that form no part of the claimed design.
